DISH RACK OR THE LIKE

Sue Urth Irwin, Los Angeles, Calif.

Application October 10, 1949, Serial No. 5,397

Term of patent 14 years

(Cl. D44—29)

To all whom it may concern:

Be it known that I, Sue Urth Irwin, a citizen of the United States of America, residing in Los Angeles, county of Los Angeles, and State of California, have invented a new, original, and ornamental Design for a Dish Rack or the like, of which the following is a specification, reference being had to the accompanying drawing, forming a part hereof.

Fig. 1 is a top plan view of a dish rack or the like embodying my new design.

Fig. 2 is a side elevational view of the dish rack or the like.

Fig. 3 is a cross section taken on the line 3—3 of Fig. 2.

I claim:

The ornamental design for a dish rack or the like, as shown.

SUE URTH IRWIN.
